UNITED STATES PATENT OFFICE.

WILLIAM P. WILBER, OF PROVIDENCE, RHODE ISLAND.

SELF-CLOSING COMPARTMENT-DOORS.

1,071,845.

Specification of Letters Patent.

Patented Sept. 2, 1913.

Application filed November 23, 1912. Serial No. 733,222.

To all whom it may concern:

Be it known that I, WILLIAM P. WILBER, a citizen of the United States, residing at Providence, in the county of Providence and State of Rhode Island, have invented certain new and useful Improvements in Self-Closing Compartment-Doors, of which the following is a specification.

This invention comprehends certain new and useful improvements in that type of ship which is divided into a plurality of communicating compartments and relates more particularly to means whereby a flow of water into any one of said compartments will automatically close the compartment against communication with the adjoining ones.

Another and more specific object of the invention resides in the provision of a self closing compartment door, which, when in its open position, forms a portion of the compartment bottom and which, when raised by an inflow of water, will close a doorway formed in one side of the compartment.

As is well known, compartment doors which are dependent upon human agencies for their closing, very often in times of danger, refuse to operate, whereby a great loss of life is incurred, and my improved door is designed to overcome this objection.

With these and other objects in view, as will become more apparent as the description proceeds, the invention consists in certain novel features of construction, combination and arrangement of parts, which will be hereinafter fully described and claimed.

For a complete understanding of the invention, reference is to be had to the following description and accompanying drawings, in which

The figure represents a fragmentary vertical sectional view through a ship.

Referring to the drawing by numerals, 1 designates the bottom of a ship, 2 vertical bulk heads or partitions, and 3 horizontal partitions. This construction divides the ship into a plurality of compartments designated by the numerals 4, 5, 6 and 7. The compartments of the same tier are made communicating by openings or doorways 8, formed into the vertical bulk heads 2 and are cut off from communication with the compartments of the next higher tier by the unbroken horizontal partitions 3. The

bottom of each compartment is formed by a pair of doors 9 and 10 and a centrally positioned strip 11, which is supported by means of a brace 12. The doors 9 and 10 are provided upon their ends with the trunnions 13, which are received within angular brackets 14, secured to the bulk heads 2 and formed with the horizontal slots 15. To the under side of each of the doors, an air-tight tank 16 is secured. These tanks are preferably formed of sheet-metal and provided with downwardly converging bottom walls.

It will be seen upon reference to the drawing, that should the bottom of the ship be broken away, as indicated, water will flow into the compartment 7 and raise the pivoted doors 9 and 10 to a vertical position, at which time the openings 8 in the vertical bulk heads will be closed automatically. The slotted brackets 14 permit of the necessary movement of the trunnions 13, whereby the doors 9 and 10 may be positioned flatly against the bulk heads 2.

It will be seen that I have provided an improved self closing compartment door, which will always operate to close its compartment from communication with adjoining compartments when water flows into it. The doors are of very simple construction, may be very cheaply manufactured and installed, and serve also as floors for the compartments.

It is to be understood that while I have shown and described the preferred embodiment of my invention, I do not wish to be limited to this exact construction, but may make such changes as will fall within the scope and spirit of the invention.

Having thus described my invention, what I claim is:

1. The combination with a ship divided into a number of communication compartments, of self closing doors for the same, said doors being hinged to the side walls of the compartments and forming, when in their open position, bottoms for the same, and air tanks carried by said doors, whereby an inflow of water will move the doors to a vertical position, at which time the compartment will be cut off from communication with the adjoining compartments.

2. The combination with a ship having a plurality of vertical and horizontal partitions forming compartments, said vertical partitions being formed with doorways, of

self closing compartment doors, said doors being formed with trunnions, slotted brackets secured to said vertical partitions and receiving said trunnions, the doors, when in 5 their open position, forming the bottom of the compartment, and air tanks secured to said doors, whereby an inflow of water will cause the doors of any compartment to swing about the trunnions as pivots and

close the door ways formed in the sides of 10 said compartment.

In testimony whereof I affix my signature in presence of two witnesses.

WILLIAM P. WILBER.
